NEW JERSEY

ARTIFICIAL-EYE MOUNT

Application filed August 13, 1929. Serial No. 385,563.

This invention relates to new and useful improvements in figure toys and more particularly to a novel artificial eye mount. The principal object of the invention is to provide an eye mount for figure toys which is capable of being assembled in the head of a figure toy in a much less length of time than is required to place eyes of this type in toys at present, thus saving labor and expenses incidental thereto.

Another important object of the invention is to provide an improved eye mount which will eliminate the constant breaking of the eye and heads which now occurs, due mostly to the impractical construction of the present types of eye mounts, which necessitates considerable inconvenience and expert skill to properly assemble.

Still another object of importance is to provide an artificial eye mount having means whereby the eye balls will be firmly maintained in position, yet allowing an even movement in operation.

Still another object of importance is to provide a mount of the character mentioned which will remain positioned within the figure toy head by reason of its spring tendency.

A further important object of the invention is to provide an eye mount assembly including piercing members which will not puncture the figure toy head due to limiting means on the said assembly.

These and numerous other important objects and advantages of the invention will become more apparent to the reader after considering the invention as described and claimed hereinafter.

In the drawings:

Figure 1 represents a fragmentary vertical sectional view through a figure toy head and the assembled eye mount therein.

Figure 2 represents a fragmentary inside elevation of the head showing the mount assembled therein.

Figure 3 represents a side elevation of the spring bar.

Figure 4 represents a side elevation of the shaft saddle.

Figure 5 represents a perspective view of the tensioning plate for the shaft.

Figure 6 represents a horizontal sectional view, taken substantially on the line 6—6 of Figure 2.

Figure 7 represents a fragmentary vertical sectional view taken substantially on the line 7—7 of Figure 2.

Referring to the drawings wherein like numerals designate like parts, it will be seen that the numeral 5 denotes a figure toy head of the usual construction and which is provided with the usual eye opening and socket for receiving artificial eyes of the movable type. The inner side of the forehead portion of the toy head is provided with the shoulder 6, which gradually merges off in the manner clearly shown in Figures 1 and 2. This shoulder 6 is provided with a depending lug 7, the purpose of which will be fully explained hereinafter. The inner side of the neck portion of the doll head is also provided with a shoulder 8, which merges off to the normal thickness of the neck wall.

The present invention includes a support, such as that shown in Figure 3, which is in the form of an elongated bar of some suitable spring metal, the bar being denoted by the numeral 9. At the intermediacy of the bar, the longitudinal edge portions thereof are notched at opposed points as at 10, while the upper end portion of the bar is cut away at its longitudinal edge portion to provide a reduced neck 11. A head 12 is provided at the upper end of the bar and the longitudinal edge portions of the bar at this point are cut off to provide the converging edges 13—13.

This head 12 is provided with a recess 14, and the presence of this recess determines the pointed furcations 15—15. From the neck portion 11 of the bar, a corrugation or elongated bulge 16 extends toward the lower end of the bar and also tapers in this direction to the point 17. Between the point 17 and the shoulder 18, the bar curves laterally as clearly disclosed in Figure 1, so that the bar may accommodate the chin portion of the toy head. The lower end portion of the bar is provided with a pair of depending prongs 19—19 extending from the shoulder portion 18 and depending from the shoulder 18 and from a point between the prongs 19—19 is

the tongue 20, which tongue is curved longitudinally away from the neck of the doll in the manner shown in Figure 1. The shaft 21 for supporting the eye balls 22 is provided with a crank 23, at each end thereof for disposition through the struck out loop 24 of the corresponding eye ball cup 25.

Obviously there must be a snug fit of the crank within the loop 24, so that while the cup may be adjusted thereon, the same must maintain its position against accidental displacement.

In Figure 4 a saddle is shown for supporting the shaft 21 and this saddle comprises a plate 26, which has the vertical edge portions thereof notched at opposite points as at 27—27. The upper portion of the plate is reduced to provide a longitudinally extending tongue 28, which tongue is bent to provide an offset 29, at its intermediacy. The intermediacy of the shaft 21 is loosely supported within the offset 29 of the said saddle. The plate 26 engages against the bar 9 so that the edge portions of the notches 27—27 and 10—10 of the plate 26 and bar 9 coincide, so that the metallic strap 30 may have its end portion bent behind the bar 9 and across the plate 26 and tensioning member shown in Figure 5, so that the seating thereof within the notches 27—27 and 10—10 will prevent longitudinal movement of the said parts with respect to each other. The tensioning member shown in Figure 5, comprises a plate 31, which is reduced at its upper end portion and bifurcated to provide the pair of legs 32—32. This tensioning member is of spring metal and the legs 32—32 are suitably spaced apart to receive the offset portion 29 of the saddle and are each provided at its intermediacy with an offset 33. These offsets 33 bear against the shaft 21, in the manner clearly shown in Figures 1 and 2 so as to tensionally urge the eye balls 22, toward the sockets of the figure toy head. The plate 31 is notched at 32' to receive strap 30. A V-shaped frame 34 (clearly shown in Figures 1 and 2) has one end secured to one crank 23, of the shaft 21, as at 35, while its opposite end, although being secured also to the opposite crank 23, is provided with an extension 36, which extension curves inwardly and then longitudinally of the frame and substantially on the longitudinal axis thereof. The weight generally referred to by the numeral 37 is provided on the bight portion 38 of the frame 34 and comprises an elongated piece of steel plate or in fact, some other suitable metal, denoted by the numeral 39 in the drawings. This piece of metal is bent upon itself for clamped engagement against the bight portion of the frame 34, and is provided with registering openings in its opposed portion for receiving the resilient plug 40. This plug tapers and its enlarged end portion

protrudes in the direction of the shoulder 8 of the figure toy head.

When the aforementioned parts are properly assembled on the bar 9, the bar and its supported mechanism is inserted into the head of the figure toy and the pointed furcations 15—15 are pressed against the shoulder 6 so that the recess 14 receives the depending lug 7 on said shoulder. By forcing the bar 9 in the direction of the shoulder, the said furcations will bite into the shoulder to a limited extent. By now flexing the bar 9 toward the face of the toy and engaging the prongs 19—19 against the upward face of the shoulder 8, the release of the bar 9 will result in the driving of these prongs into the shoulder by reason of the primary flexed nature of the bar and its tensional reaction.

The foregoing manipulations are all carried out manually and by grasping the tongue 20, in contradistinction to the conventional methods of inserting these eye mount assemblies by tool or by machine.

Obviously, when the toy head is tilted, the pendulum consisting of the frame 34, weight 37, and shaft 21, will swing to shift the position of the eye balls 22, with respect to the eye sockets of the head 5. To limit this closing motion of the eye balls, the extension 36 of the frame will abut the upper portion of the shoulder 6, while on the return stroke of the pendulum, that is, when the eyes are being opened, the resilient plug 40 will strike against the shoulder 8 to absorb shock and to prevent flickering of the eye balls due to the rebounds of the pendulum.

It is to be understood that during the manufacture of this novel eye mount assembly, various changes in the shape, size, and materials may be resorted to, without departing from the spirit and scope of the invention, as claimed hereinafter.

Having thus described the invention, what is claimed is:

1. In a figure toy, in combination, a hollow figure toy head, a pair of vertically spaced protuberances on the inner side of the head, and a spring bar for movably supporting a pair of artificial eyes and for tensioned interposition between said protuberances, said bar being provided with means to rigidify a portion thereof, said means comprising a longitudinally extending corrugation on the bar at which portion the eyes are mounted, while the remaining portion of the bar remains springy to permit flexing thereof.

2. In a figure toy, in combination, a hollow figure toy head, a pair of vertically spaced protuberances on the inner side of the head, and a spring bar for movably supporting a pair of artificial eyes and for tensioned interposition between said protuberances, said bar being provided with means to rigidify a portion thereof, said means comprising a trans-

versely curved and longitudinally extending bulge.

3. An optical mount for figure toys comprising a main bar, an eye ball supporting shaft swingably mounted on the bar, a pendulum for said shaft, said pendulum comprising a substantially V-shaped frame, the leg portions of the frame being secured to the shaft, and a weight at the apex of said frame, said weight comprising a piece of relatively heavy metal bent upon itself and having the said apex of the frame clamped between the opposed portions thereof, said opposed portions being provided with registering openings, and a resilient plug for disposition through said opening and in a manner whereby it may protrude beyond one side of the weight for absorbing the shock of the same when it engages the figure toy head.

20 4. A support for toy eyes comprising an elongated bar of spring material, a longitudinally extending rigidifying member at one end of the bar and at which portion toy eyes are mounted, the opposite end portion of the bar being capable of being flexed to permit the tensional interposition of the bar between the pair of spaced abutments.

5. A support for toy eyes comprising an elongated bar of spring material, a longitudinally extending rigidifying member at one end of the bar and at which portion toy eyes are mounted, the opposite end portion of the bar being capable of being flexed to permit the tensional interposition of the bar between the pair of spaced abutments, and a tongue at the last mentioned end portion of the bar to permit manual actuation thereof.

In testimony whereof they affix their signatures.
